UNITED STATES PATENT OFFICE.

EUGENE ATWOOD, OF STONINGTON, CONNECTICUT, ASSIGNOR TO ATWOOD MACHINE COMPANY, OF STONINGTON, CONNECTICUT, A CORPORATION OF NEW JERSEY.

SPINNING AND TWISTING SPINDLE.

Application filed March 9, 1922. Serial No. 542,349.

To all whom it may concern:

Be it known that I, EUGENE ATWOOD, a citizen of the United States, and resident of Stonington, in the county of New London 5 and State of Connecticut, have invented a new and useful Improvement in Spinning and Twisting Spindles, of which the following is a specification.

The object of my invention is to provide 10 certain improvements in the construction, form and arrangement of the several parts of a self oiling spindle of the step and bolster type, whereby a thorough lubrication of the step and bolster bearings is obtained.

15 My invention more particularly comprises a self oiling spindle of the step and bolster type in which a removable cylindrical cup which forms an oil reservoir, surrounds the step bearing portion and a removable tube 20 surrounds the uprising bolster bearing portion of the case.

A practical embodiment of my invention is represented in the accompanying drawings in which

25 Fig. 1 represents the spindle in side elevation.

Fig. 2 represents a vertical central section taken in the plane of the line II—II of Fig. 1.

30 Fig. 3 represents a cross section taken in the plane of the line III—III of Fig. 1.

Fig. 4 represents a cross section taken in the plane of the line IV—IV of Fig. 2.

The spindle blade 1 is provided with the 35 usual whirl 2. The support for the spindle comprises the case 3, having a depending step bearing portion 4 and an uprising bolster bearing portion 5. An uprising tube 6 surrounds the bolster bearing portion 5 and, in the present instance, is spaced therefrom by providing an annular series of lugs 7 projecting from the bolster bearing portion near its top, the bottom of the tube 6 snugly fitting over the enlarged base of the bolster 40 bearing portion and resting on the top of the spindle rail flange 8 of the case 3. Oil circulating holes 9 lead through the side wall 45 of the bolster bearing portion 5.

A cylindrical oil cup 10 surrounds the 50 step bearing portion 4 and has an interior

screw threaded engagement 11 therewith, just beneath the flange 8. An oil tight joint is ensured between the oil cup and step bearing portion by providing the step bearing portion with a conical seat 12 arranged to 55 have an extended engagement with a conical shoulder 13 in the bore of the cup 10. The step bearing portion 4 is preferably tapered below the conical portion 12, leaving an oil chamber 14 of substantial size 60 within the cup 10, the bottom of which extends a short distance below the bottom of the step bearing portion. A vertically elongated oil circulating port 15 extends through the wall of the step bearing portion 4. This 65 cup 10 is provided with an exteriorly screw threaded portion 16 near its bottom for the reception of the nut 17 between which nut and the spindle rail, the usual coil spring 18 may be inserted for yieldingly securing 70 the spindle case to the rail.

From the above description it will be seen that I have provided an oil reservoir of novel form in the bottom of which, below the step bearing, any sediment or foreign 75 matter may collect, and which may be very readily removed and replaced.

It is evident that various changes may be resorted to in the construction, form and arrangement of the several parts without departing from the spirit and scope of my invention; hence, I do not wish to be limited to the particular embodiment herein shown and described, but

What I claim is:

1. A self oiling spindle of the step and bolster type comprising a case having bolster and step bearing portions, a removable oil cup surrounding the step bearing portion, and a removable tube surrounding and 80 spaced from the bolster bearing portion.

2. A self oiling spindle of the step and bolster type comprising a case having bolster and step bearing portions, a removable oil cup surrounding the step bearing portion, a removable tube surrounding and 85 spaced from the bolster bearing portion, and oil ports through the walls of the step and bolster bearing portions.

3. A self oiling spindle of the step and 100

bolster type comprising a case having bolster and step bearing portions, a removable oil cup surrounding the step bearing portion, a removable tube surrounding the bolster bearing portion, said bolster bearing portion having an enlarged base fitting within the bottom of the tube, and lugs near its top for spacing the tube from the bolster

bearing portion, and oil ports through the walls of the bolster and step bearing portions. ¹⁰

In testimony, that I claim the foregoing as my invention, I have signed my name this 7th day of March 1922.

EUGENE ATWOOD.
